CABINET SMOKE STAND

George P. Williams and George Williams,
Portland, Oreg.

Application December 10, 1947, Serial No. 790,810

21 Claims. (Cl. 312—150)

1

This invention relates to novel and useful improvements in smokers' articles.

An object of this invention is to supply an ornamental support or stand with a recess therein and hinged closure plates attached to the stand adjacent the recess, which plates may be pivotally or hingedly actuated thereby rendering access to the interior of the recess.

Another purpose of this invention is to selectively raise and lower the plates, hingedly actuating them at the same time and simultaneously slide a pair of receptacles in the place of the plates.

Another object of this invention is to slide a rod parallel to the longitudinal axis of the support carrying with it means for urging the receptacle to a selected position.

Another purpose of this invention is to provide an extremely attractive device which is utilized as an article of furniture for retaining various and sundry articles pertinent to smoking.

Ancillary objects and features of novelty will become apparent to those skilled in the art, in following the description of the preferred form of the invention, illustrated in the accompanying drawings, wherein:

Figure 1 is an elevational view of the preferred form of the invention;

Figure 2 is a plan view of the invention shown in Figure 1;

Figure 3 is a sectional view taken substantially on the line 3—3 of Figure 2 and in the direction of the arrows with the receptacles and operating mechanism in full elevation;

Figure 4 is a sectional view taken on the line 4—4 of Figure 3 and in the direction of the arrows;

Figure 5 is a sectional view taken substantially on the line 5—5 of Figure 3 and in the direction of the arrows;

Figure 6 is a perspective view of the hinge means for connecting the two closure plates utilized in association with the invention;

Figure 7 is an enlarged perspective view of the actuator plates secured to the actuator rod and utilizing in association with the invention;

Figure 8 is a sectional view taken substantially on the line 8—8 of Figure 3 and in the direction of the arrows and with the receptacles in closed position;

Figure 9 is a perspective view of the receptacle or block forming part of the present invention;

Figure 10 is a perspective view of the crank

2

forming part of the present invention utilized in association therewith;

Figure 11 is a longitudinally sectional view illustrating particularly the recess and other pertinent portions of the invention and taken on the line 11—11 of Figure 2;

Figure 12 is a sectional view taken on the line 12—12 of Figure 3 and in the direction of the arrows;

Figure 13 is a plan view of the device, portions being removed to illustrate details of construction and to illustrate the receptacles in the closed position, and;

Figure 14 is a perspective view of the housing used for journaling the rollers, seen in Figure 3.

This invention has been developed to provide a device for retaining smokers' articles. It has been constructed in order to be of utility as an article of furniture in domiciles, office buildings and the like. The preferred material of construction is a select grade of wood; however, it is within the purview of the present invention to utilize metals, commercial plastic and other selected materials.

25 A stand or support 10 is provided with a recess 12 at one end thereof and a bore 14 extending longitudinally of the said stand or support. This bore communicates with the recess 12 and as is seen in Figure 3, and an enlargement of the said bore is provided with a housing 16. This housing seats in the enlargement of the bore 14 and contains a pair of rollers 18 and 20, respectively. These rollers are journalled on, and by means of, suitable shafts 17 and 19. The preferred material of construction of the rollers is resilient in nature such as various forms of rubber.

35 The shaft 17 is provided with an extension 22 (see Figures 4 and 14), which projects through the support 10. A suitable knob or handle is then supplied on the said extension 22 for manual operation of the rollers. By manipulating the knob 23 on said rod 22 the roller 18 will be turned.

45 A rod 24 extends through a line of apertures (one of which is indicated at 26, Figure 14) in the housing 16 and operatively engages both of the rollers 18 and 20. It may now be seen that upon manipulation of the rod 22, the rod 24 will be urged through the aligned apertures 26 through the medium of the rollers 18 and 20 which frictionally engage said rod 24 to operate it and hold it in the desired position.

50 A pair of plates 28 and 30 respectively shown in Figure 3 having beveled edges 32 are provided

with cooperating recesses 34 and 36 respectively and a hinge generally indicated at 38 connects these plates.

Referring to Figure 6 it will be seen that a pair of hinge plates 40 and 42 respectively are supplied with a plurality of apertures in order to receive conventional screws or the like. One of the said hinge plates is secured to the plate 28 while the other hinge plate 42 is secured to the plate 30. It is noted at this point that decorative designs may be supplied on the said plates 28 and 30 such as the pipes illustrated in Figure 3.

Since the rod 24 is operatively associated with the hinge pin 44, actuation of the said rod 24 downwardly will fold the plates 28 and 30 respectively about this hinge pin as an axis. This renders it possible for the hinge plates to be drawn into the recess 12.

To assist in guiding the rod 24 in its travel, a piston head 48 is secured to the said rod 24 and is slidable in the bore 14.

A pair of receptacles or blocks, generally indicated at 50 are provided in the said recess 12. These blocks are substantially identical, the only difference being in the upper surface thereof, wherein various and sundry appurtenances such as ash trays, cigar, cigarette and cigarette lighter holders may be positioned. Noting Figure 9 it will be seen that the general configuration of the receptacles 50 is similar to an inverted L having one beveled surface 52 at the terminal portion of one leg thereof. The interior of the recess 12 is also beveled to render it complementary to this beveled portion (see Figure 3).

In order to slidably mount the receptacles 50 in the said recess there is supplied a groove 54 on each side thereof which rides on a tongue or rib 56 provided on the inner surface of the recess 12. By this construction the receptacle 50 is slidable in the said recess.

A slot 58 transverse to the said groove 54 is provided in the leg of the L-shape receptacle 50. A crank 60 is provided with a right angular end 62 which is slidable in the said slot 58. The said crank 60 is journalled in one of the identical bosses or bearings 64 which is provided on an extension of the housing 16. Extensions 66 and 68 respectively which are provided mutually at right angles to each other form a part of said crank 60. There are two cranks 60 and two receptacles 50 used. Each has one crank connected therewith for slidably operating the receptacle, the arrangement being such as to cause operation of the receptacles simultaneously.

Means for actuating the said crank 60 pivotally about the boss 64 is provided. This means may be noted particularly in Figure 7 wherein a pair of actuator plates 70 and 72 respectively are mutually spaced on the rod 24. The upper plate 70 is of larger length than the lower plate 72. As the rod 24 is lowered the lower plate 72 will pass the extensions 68 thereby permitting the plate 70 to urge the right angular extensions 68 downwardly and thus, by pivotal action at 64, the crank end 62 is urged upwardly in the slot 58 and in this manner urges the receptacle 50 toward the center of the recess 12. Since this construction is duplicated, the opposite receptacle will also be urged in the same manner to completely close the open portion of the recess 12 wherein the plates 28 and 30 respectively were formally seated. In returning the receptacles to the sides of the recess 12 and in returning the plates 28 and 30 to their position of closing the said recess 12, the exten-

sions 68 are urged pivotally in a reverse direction by means of the plate 72.

While there has been described and illustrated by the preferred form of the invention, it is apparent that variations may be made without departing from the spirit thereof.

Having described the invention, what is claimed as new is:

1. A smoker's article comprising a support having a recess at the upper portion thereof and a bore communicating with said recess, shoulders in said support adjacent said recess, plates resting on said shoulders, means for hingedly connecting said plates, means in said bore for raising and lowering said plates including an actuating rod operatively connected with said plates, a pair of rollers disposed in said recess with said rod passed therethrough and means operatively connected with one of said rollers and operable exteriorly of said support for actuating that roller to raise and lower said rod.

2. A smoker's article comprising a support having a recess at the upper portion thereof and a bore communicating with said recess, shoulders in said support adjacent said recess, plates resting on said shoulders, means hingedly connecting said plates, means in said bore for raising and lowering said plates, a receptacle in said recess, and means operatively connected with said raising and lowering means for moving said receptacle to selective positions in response to movement of said raising and lowering means.

3. A smoker's article comprising a support having a recess at the upper portion thereof and a bore communicating with said recess, shoulders in said support adjacent said recess, plates resting on said shoulders, means hingedly connecting said plates, means in said bore for raising and lowering said plates, said means including a rod, rollers journalled in said bore, means exterior of said bore and secured to one of said rollers for actuation thereof, said rod being interposed between the rollers and secured to said hingedly connecting means, a receptacle slidably positioned in said recess, and means connected with said plate raising means for moving said receptacle in selected positions.

4. A smoker's article comprising a support having a recess at the upper portion thereof and a bore communicating with said recess, shoulders in said support adjacent said recess, plates resting on said shoulders, means hingedly connecting said plates, means in said bore for raising and lowering said plates, said means including a rod, rollers journalled in said bore, means exterior of said bore and secured to one of said rollers for actuation thereof, said rod being interposed between the rollers and secured to said hingedly connecting means, a receptacle slidably positioned in said recess, means actuated by said plate raising means for moving said receptacle in selected positions, said receptacle moving means including a crank pivoted to said support within said recess having one end slidably secured to said receptacle, and spaced actuator plates secured to said rod engageable with the free end of said crank for pivotal actuation thereof.

5. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slidably in said bore, means for raising and lowering said rod in said bore, and means secured to said

support for actuating said raising and lowering means.

6. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, said raising and lowering means comprising a housing having said rod extending therethrough, and a pair of rollers journaled in said housing flanking and engaging said rod.

7. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, and means actuated by said rod for positioning said receptacle.

8. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, means actuated by said rod for positioning said receptacle, said last mentioned means including a groove in said receptacle, a crank pivoted to said support within said recess and having one end thereof slidably disposed in said groove, and means secured to said rod for pivotally actuating said crank.

9. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, means actuated by said rod for positioning said receptacle, said last mentioned means including a groove in said receptacle, a crank pivoted to said support within said recess and having one end thereof slidably disposed in said groove, means secured to said rod for pivotally actuating said crank, and said last mentioned means including a pair of spaced actuator plates secured to said rod for successively engaging the free end of said crank when said rod is raised and lowered.

10. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting

said receptacle in said recess, means actuated by said rod for positioning said receptacle, said last mentioned means including a groove in said receptacle, a crank pivoted to said support within said recess and having one end thereof slidably received in said groove, means secured to said rod for pivotally actuating said crank, said actuator plates being of different lengths whereby the free end of the crank may be urged a predetermined distance then slip to the next adjacent plate during a single cycle of operation of the rod.

11. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, means actuated by said rod for positioning said receptacle, said raising and lowering means comprising a housing having said rod extending therethrough, and a pair of rollers flanking and engaging said rod and journaled in said housing.

12. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, means actuated by said rod for positioning said receptacle, said last mentioned means including a groove in said receptacle, a crank pivoted to said support within said recess and having one end thereof slidably disposed in said groove, means secured to said rod for pivotally actuating said crank, said last mentioned means including a pair of spaced actuator plates secured to said rod for engaging the free end of said crank, said raising and lowering means comprising a housing having said rod extending therethrough, and a pair of rollers journaled in said housing and flanking and engaging said rod.

13. In a smoker's article, a support having a recess at one end and a bore communicating with said recess, shoulders on said support adjacent said recess, a pair of plates seated on said shoulders, a hinge connecting said plates, a rod secured to said hinge having a piston head thereon slideable in said bore, means for raising and lowering said rod in said bore, means secured to said support for actuating said raising and lowering means, a receptacle, means slidably mounting said receptacle in said recess, means actuated by said rod for positioning said receptacle, said last mentioned means including a groove in said receptacle, a crank pivoted to said support within said recess and having one end thereof slidably disposed in said groove, means secured to said rod for pivotally actuating said crank, said actuator plates being of different lengths whereby the free end of the crank may be urged a predetermined distance then slip to the next adjacent plate during a single cycle of operation of the rod, said raising and lowering means comprising a housing having said rod extending therethrough, and a pair

of rollers engaging said rod and journaled in said housing.

14. In a smoker's article, a stand having a recess at its upper end, tracks disposed in said recess, a pair of receptacles, each receptacle having grooves which are disposed in slidable relationship on said tracks, a rod disposed in said support and having a pair of plates fixed thereto, means for raising and lowering said rod, and means engaged by said plates and pivoted in said recess and operatively connected with said receptacles for sliding said receptacles on said tracks in response to movement of said rod.

15. The combination of claim 14 and said last-mentioned means comprising a pair of cranks which are pivoted to said stand and which have bent end portions, the lower bent end portions being engaged by said plates and the upper end portions slidably connected with said receptacles.

16. A smoking stand comprising a support, tracks in said smoking stand support, receptacles slidably disposed in said support, cranks having their upper ends slidably connected with said receptacles, an operating rod axially movably disposed in said support and having a large and a small plate fixed thereto, the lower bent ends of said cranks being engaged and pivoted by said large plate when said rod is lowered, thereby sliding said receptacles to one position and the lower bent ends of said cranks being engaged and operated by said small plate when said rod is raised, to thereby move said receptacles to another position.

17. In a smoking stand, a support which has a recess at the top thereof, horizontal tracks in said recess, receptacles having horizontal grooves on opposite surfaces thereof, said tracks being disposed in said groove thereby mounting said receptacles for sliding movement, said receptacles having vertical grooves therein, cranks pivoted in said recess and to said support, the upper ends of said cranks being slidably disposed in said vertical grooves, an operating rod arranged for axial movement in a vertical plane with means mounting said operating rod in said support, rollers carried by said support and engaging said rod together with means for operating at least one of said rollers to thereby raise and lower said rod, and said rod having means thereon engaging operatively the lower ends of said cranks to pivot said cranks, thereby sliding said receptacles to selected positions.

18. In a smoking stand, a support which has a recess at the top thereof, horizontal tracks in said recess, receptacles having horizontal grooves on opposite surfaces thereof, said tracks being disposed in said groove thereby mounting said receptacles for sliding movement, said receptacles having vertical grooves therein, cranks pivoted in said recess and to said support, the upper ends

of said cranks being slidably disposed in said vertical grooves, an operating rod arranged for axial movement in a vertical plane with means mounting said operating rod in said support, rollers carried by said support and engaging said rod together with means for operating at least one of said rollers to thereby raise and lower said rod, and said rod having means thereon engaging operatively the lower ends of said cranks to pivot said cranks, thereby sliding said receptacles to selected positions, including a pair of juxtaposed spaced plates fixed to said rod, the upper of said juxtaposed plates being longer than the lower of said plates, whereby when said rod is lowered said upper plate engages and actuates said cranks to operate said receptacles and when said rod is raised, the lower of said plates engages and operates said cranks in the opposite direction.

19. The combination of claim 17 and the upper end of said rod having a hinge secured thereto, and cover plates disposed on said support and superposed with respect to said receptacles, and said cover plates being connected to said hinge so that said cover plates are hingedly operated when said rod is lowered.

20. The combination of claim 17 and the lower end of said rod having a guide thereon, said support having a vertical passage therein with said guide disposed in said passage, thereby limiting the movement of said rod to movement in a vertical plane.

21. The combination of claim 17 and the lower end of said rod having a guide thereon, said support having a vertical passage therein with said guide disposed in said passage, thereby limiting the movement of said rod to movement in a vertical plane, said receptacles consisting of a pair of blocks with the upper surfaces thereof having recesses therein of various configurations to accommodate various smoker's articles and appurtenances.
